(57) **CLAIM**

The ornamental design for a sight module, as shown and described.

DESCRIPTION

FIG. 1 is a perspective view of a sight module showing my new design, illustrating a fiber optic sight and a ring-shaped sight element being mounted on top of two ends of the body. FIG. 2 is a front view of the sight module.

FIG. 3 is a rear view of the sight module.

FIG. 4 is a left view of the sight module.

FIG. 5 is a right view of the sight module.

FIG. 6 is a top view of the sight module.

FIG. 7 is a bottom view of the sight module.

FIG. 8 is a perspective view of the sight module, illustrating the ring-shaped sight element being detachably and selectively mounted to the body at different locations.

FIG. 9 is a perspective view of the sight module, showing the reflex dot being detachably mounted to an end portion of the body.

FIG. 10 is a perspective view of the sight module, showing the reflex dot being detachably mounted to a mid-portion of the body.

FIG. 11 is a perspective view of the sight module, showing the sight module being detachably mounted to a firearm; and, FIG. 12 is a rear perspective view of the sight module, showing a blade-type sight element as a replacement of the fiber optic sight being detachably mounted to the body.

The broken line portion of the figure drawings is included to show unclaimed subject matter only and forms no part of the claimed design.
